COMBINATION SPOUT AND SHOWER FIXTURE

Gilbert L. Hartmann and Stephen A. Slinde, Milwaukee, Wis., assignors to Milwaukee Flush Valve Company, Milwaukee, Wis., a corporation of Wisconsin

Application February 19, 1953, Serial No. 337,746

10 Claims. (Cl. 137—610)

1 Our present invention relates in general to improvements in plumbing accessories, and relates more specifically to improvements in the construction and operation of combination spout and shower water dispensing fixtures.

The primary object of the present invention is to provide an improved convertible combination spout and shower plumbing fixture which is exceedingly simple and compact in construction and highly efficient in operation.

Numerous plumbing fixtures of different types for interchangeably delivering warm or cold water to either a spout or a shower head, have heretofore been proposed and used with varying degrees of success; but practically all of these prior combination fixtures are either too complicated and unreliable in operation or they are too difficult to install in cramped quarters and at moderate cost, as in vehicle drawn trailers or the like. Many of these previous convertible liquid dispensing fixtures are also relatively dangerous since they do not permit rapid and effective conversion from one use to another, and all of the prior devices are objectionable for one reason or another.

It is therefore an object of this invention to provide an improved spout-shower liquid dispensing fixture, which obviates all of the above mentioned objectionable features, and which may be easily installed within limited space.

Another important object of our invention is to provide a convertible plumbing fixture of the spout or shower type, which comprises relatively few simple but durable parts adapted to be readily manufactured and assembled at low cost to produce a unit which is conveniently manipulable to convert it from one use to another.

A further important object of the invention is to provide an improved flow control valve assembly for combination spout and shower fixtures, which will insure an abundant flow of liquid to either the spout or the shower nozzle to the exclusion of the other, without utilizing complicated packings requiring frequent attention and replacement.

Still another important object of the present invention is to provide a compact but highly effective jet-spray convertible plumbing fixture especially adapted for installation in vehicle drawn trailers or similar cramped localities, and which may be installed by a novice and safely manipulated.

These and other objects and advantages of the improvement will be apparent from the following description, from which it may be noted that the gist of our invention is the provision of a

2 convertible spout-shower liquid dispensing fixture in which the water distributing casing is provided with a bore having spout and shower outlets on its opposite sides, a nozzle secured to the casing and extending eccentrically within and along the bore and having spaced liquid delivery orifices directed toward the spout outlet side of the bore, a tubular valve body slidable along the bore and having a local opening on one side alignable with one of the nozzle orifices and with the spout outlet while its opposite side is slotted longitudinally for slidable cooperation with the eccentric nozzle, and a member manipulable from the exterior of the casing for moving the valve body along the casing bore.

A clear conception of the several features constituting the present invention and of the construction and operation of a typical commercial convertible plumbing fixture embodying the same, may be had by referring to the drawing accompanying and forming a part of this specification in which like reference characters designate the same or similar parts in the various views.

25 Fig. 1 is a fragmentary perspective view of one of the improved combination spout and shower fixtures, showing the hot and cold water supply valves and the spout and shower head, but having a portion of the shower supply conduit broken away;

Fig. 2 is a fragmentary central vertical section through the fixture of Fig. 1, with a portion of the shower omitted and showing the diverter valve body in spouting position;

Fig. 3 is a fragmentary section through the improved fixture, similar to that of Fig. 2, but showing the diverter valve body in showering position;

Fig. 4 is a transverse horizontal section through the same spout-shower fixture, taken along the line 4—4 of Fig. 2; and

Fig. 5 is an elevation of the diverter valve body and its actuating knob, looking toward the longitudinally slotted side of the body.

45 While the invention has been illustrated and described as being especially applicable to small and compact warm and cold water supply fixtures of the convertible spout and shower type adapted for vehicle use, it is not our desire or intent to unnecessarily restrict the utility of the improved features by virtue of this limited showing; and it is also contemplated that specific descriptive terms employed herein be given the broadest possible interpretation consistent with the disclosure.

55 Referring to the drawing, the improved spout

and shower plumbing fixture illustrated therein, comprises in general a main hot and cold water mixing and distribution casing 6 provided with a central upright cylindrical bore 7 having a spout outlet 8 on one side and a shower outlet 9 on the opposite side thereof; a vertically elongated upright nozzle 10 fixedly secured to the casing 6 at the lower end and eccentrically of the bore 7 and having a central liquid supply port 11 communicating with vertically spaced liquid delivery orifices 12, 13 directed toward the spout outlet side of the bore 7; a tubular valve body 14 snugly slidably along the bore 7 and having a local upper opening 15 on one side which is alineable with the upper nozzle orifice 12 and with the spout outlet 8, while its opposite side is provided with an elongated slot 16 slidably cooperable with the eccentrically disposed fixed nozzle 10; a handle or actuating knob 17 connected to the valve body 14 by a stem or rod 18 for moving this body along the bore 7; a liquid dispensing spout 19 associated with the front of the body 6 in open communication with the outlet 8; a shower nozzle or spray head 20 connected by an elongated goose-neck conduit 21 with the shower outlet 9 of the casing 7; and hot and cold liquid supply valves 22, 23 respectively, adapted to deliver regulated quantities of water to the port 11 of the nozzle 10 through a header 24 secured to the bottom of the casing 6.

The casing 6 and the spout 19 may be formed integral with each other, and the liquid supply and initial mixing header 24 may be attached to the lower closure wall 25 of the casing bore 7 by screw thread or otherwise, while the upright nozzle 10 may be likewise firmly secured to this bottom closure wall 25 eccentrically of the bore 7. The header 24 may also be concealed by a sheet-metal escutcheon 26 which likewise conceals the bodies of the hot and cold water supply valves 22, 23, and these valves may be of ordinary and well known construction and are manually controllable by means of independently operable handles 27, 28 respectively so as to admit any desired relative proportions of hot and cold liquid to the mixing header 24 and to the nozzle port 11.

The stationary distributing nozzle 10 may be formed hexagonal or otherwise polygonal, as shown in Fig. 4, in order to permit it to be readily applied to the lower casing wall through the upper open end of the bore 7 before the valve body 14 has been inserted, and this upper bore end is normally sealed by a screw plug 29 having a central opening through which the rod 18 of the actuating knob 17 is snugly slidably confined. The upper extremity of the tubular valve body 14 is closed by a top plate 30 to which the lower end of the rod 18 may be attached by fusion of metals or otherwise, and this top plate 30 is cooperable with the plug 29 to limit the upward movement of the body 14 and with the top of the nozzle 10 to likewise limit its downward travel, as illustrated in Figs. 3 and 2 respectively.

The construction of the movable valve body 14 and its cooperation with the fixed nozzle 10 are very important in obtaining most effective conversion of the fixture from spout to shower, and vice versa, and the hollow tubular valve body 14 may be formed of sheet-metal and has considerably larger internal diameter than the cross-section of the nozzle which is disposed eccentrically of the body 14 so as to provide a relatively extensive free chamber or space 31 between the delivery ends of the nozzle orifices 12, 75

13 and the front portion of the tubular wall of the body 14. The upper opening 15 of the valve body 14 is confined to the top of this body and is of such size that when the body 14 is lowered as in Fig. 2 the opening 15, spout outlet 8, and the upper orifice 12 are in alinement and in open communication with each other. The rear slot 16 extends throughout the entire vertical length of the tubular body 14 and rather snugly coats with the nozzle 10 so as to prevent the body 14 from rotating about its central axis, and when the valve body 14 is lowered as far as possible as in Fig. 2 there is only limited slit communication between the internal free space within the body and the shower outlet 9, whereas lifting of the valve body 14 into the position shown in Fig. 3 causes the front valve opening 15 to be sealed and exposes the internal valve space 31 to the outlet 9 through a considerable portion of the slot 16.

The lower nozzle orifice 13 constantly communicates with the chamber or free space 31 between the nozzle 10 and the interior of the valve body 14, some distance below the orifice 12 and the outlets 8, 9, and functions primarily to fill this space with liquid when the valves 22, 23 are opened. The spout 19 is provided with the usual downwardly directed discharge opening 32, and the shower spray nozzle or shower head 20 may be of any desired type having a plurality of spray or jet orifices 33 therein. This spray head 20 is preferably universally adjustably suspended from the upper end of the goose neck conduit 21 which may be formed of standard pipe and of any desired length, and normally has its lower end detachably secured as by screw threads to the rear of the casing 6 in open communication with the shower outlet 9, see Figs. 2 and 3. The escutcheon 26 which conceals the header 24 and provides a base for the casing 6 may be held in contact with the latter by the attachment of this escutcheon to the valves 22, 23 in a well known manner, and all of the externally exposed surfaces of the assemblage may be plated or otherwise finished to present a neat appearance.

When the improved combination spout and shower fixture has been constructed, assembled and installed with the supply valves 22, 23 in communication with suitable sources of hot and cold liquid under pressure, the entire assemblage will be inactive whenever the handles 27, 28 are in closed position. However, if liquid under pressure is admitted past either or both of the supply valves 22, 23 to the header 24, the admitted liquid will be initially mixed in this header and the mixture will flow through the central conduit or port 11 of the nozzle 10 and into the chamber 31 through the orifices 13, 12 in further thoroughly mixed condition. The liquid thus delivered from the lower orifice 13 will quickly fill the chamber 31 and keep it filled at all times, and the jet of liquid delivered from the upper orifice 12 may interchangeably cause a flow from either the spout 19 or from the shower head 20 depending upon the setting of the valve body 14.

If the valve body 14 is lowered to bring the local upper front opening 15 thereof into alinement with the spout outlet 8 and with the upper nozzle orifice 12, as in Fig. 2, then the jet delivered from the orifice 12 and centrally through the opening 15 and outlet 8 cooperates with the narrow slits between the opposite sides of the slot 16 and the nozzle 10, to produce a Venturi effect and to create a suction flow through these

slits from within the shower outlet 9, thereby preventing liquid from entering the shower conduit 21 while producing an abundant unrestricted flow only through the spout 19 and its discharge opening 32. In order to convert the fixture into a shower, it is only necessary to lift the valve body 14 with the aid of the knob 17 so that the spout outlet 9 and the opening 15 are sealed, and the slot 16 is openly exposed to the shower outlet 9 as in Fig. 3, whereupon the jet delivered from the upper orifice 12 of the nozzle 10 will aid in sealing the spout outlet and the liquid delivered into the chamber 31 under pressure from both orifices 12, 13 will cause an abundant unrestricted flow to the shower head 20 only through the slot 16, outlet 9, and conduit 21.

The pressure of the liquid admitted to the chamber 31 and acting upon the top plate 30 of the valve body 14 assists in lifting the body with the aid of the knob 17; and the body 14 may be readily lowered by merely pressing the knob 17 downwardly. The valve body 14 is effectively prevented from turning about its central axis by virtue of the coaction between the opposite edges of the slot 16 and the nozzle 10; and access to the valve body 14 and nozzle 10 may be readily gained by merely unscrewing the closure plug 29 at the upper end of the bore. The supply valves 22, 23 may be manipulated to obtain a mixture of hot and cold water of any desired temperature, or hot or cold liquid alone, and when the plug 29 and the valve body 14 have been removed, the nozzle 10 is also freely accessible for inspection or removal.

From the foregoing detailed description of the construction and operation of our device, it should be apparent that we have in fact provided a readily convertible spout or shower plumbing fixture which is simple, compact and durable in construction and highly effective and dependable in use. The formation and cooperation of the nozzle 10 and valve body 14 so as to form the chamber 31 is of great importance in producing rapid and highly satisfactory conversion of the fixture from one use to another and in creating unrestricted flow of the liquid to either the spout 19 or the shower head 20, while also maintaining these cooperating parts in proper position. The various parts of the unit may also be manufactured at low cost and readily assembled or dismantled, and is devoid of replaceable packings, springs, and other delicate parts requiring frequent attention. The invention has gone into highly satisfactory use functioning as hereinabove described, and the improved fixtures are especially adapted for convenient installation in relatively inaccessible and cramped localities.

It should be understood that it is not desired to limit this invention to the exact details of construction and operation of the combination spout and shower specifically shown and described herein, for various modifications within the scope of the appended claims may occur to persons skilled in the art.

We claim:

1. In a spout-shower fixture, a casing having therein a cylindrical bore and being provided with separate spout and shower outlets communicating with the opposite sides of said bore, a tubular valve body slidable within said bore and having a local opening in one side communicable with said spout outlet and an elongated slot in its opposite side communicable with said shower outlet, a liquid inlet nozzle secured

to said casing at one end of said bore and extending into said valve body and coacting with said slot to prevent rotation of the body, said nozzle having spaced liquid discharge orifices directed toward the locally open side of said body and away from the slotted side thereof, and means at the opposite end of said bore for sliding said body therealong.

2. In a spout-shower fixture, a casing having therein a cylindrical bore and being provided with separate spout and shower outlets communicating with the opposite sides of said bore, a tubular valve body slidable within said bore and having a local opening in one side communicable with said spout outlet and an elongated slot in its opposite side communicable with said shower outlet, a liquid inlet nozzle secured to said casing at one end of said bore and extending into said valve body and along and within said slot, said nozzle having a liquid discharge orifice directed through said local opening when said body is in open communication with said spout outlet, and manually manipulable means for sliding said body along said bore.

3. In a spout-shower fixture, a casing having therein a cylindrical bore and being provided with separate spout and shower outlets communicating with the opposite sides of said bore, a tubular valve body slidable within said bore and having a local opening in one side communicable with said spout outlet and an elongated slot in its opposite side communicable with said shower outlet, a fixed liquid inlet nozzle secured to said casing and extending along and within the slot of said body, said nozzle having a liquid discharge orifice directed across the interior of said body and through said local opening when the body is in open communication with said spout outlet whereby the jet delivered from said orifice through said opening produces a suction pressure at said shower outlet, and means operable from the exterior of said casing for sliding said body along said bore.

4. In a spout-shower fixture, a casing having a bore provided with segregated spout and shower outlets on opposite sides thereof, a nozzle secured to said casing and extending eccentrically within and along said bore and having spaced liquid delivery orifices directed toward said spout outlet side of the bore, a tubular valve body slidable along said bore and having a local opening on one side alineable with one of said nozzle orifices and with said spout outlet while its opposite side is slotted longitudinally for sliding cooperation with said eccentric nozzle, and a member manipulable from the exterior of said casing to move said valve body along said bore.

5. In a spout-shower fixture, a casing having a bore provided at its opposite sides with segregated spout and shower outlets, an elongated nozzle extending eccentrically within and along said bore to provide a crescent-shaped chamber near said spout outlet, said nozzle having spaced liquid delivery orifices directed across said chamber and one of which is disposed in alinement with said spout outlet, a tubular valve body slidable along said bore and having a local opening alineable with said spout outlet and with the alined orifice, said body also having a slot remote from said opening slidably cooperable with said nozzle and adapted to connect said chamber with said shower outlet, and means for moving said valve body along said bore.

6. In a spout-shower fixture, a casing having a bore provided at its opposite sides with sub-

stantially alined spout and shower outlets, a fixed nozzle extending eccentrically within and along said bore, said nozzle having an orifice spaced from but directed toward said spout outlet, a tubular valve body having a local opening alineable with said orifice and with said spout outlet and also having an elongated slot remote from said opening cooperable with said nozzle to prevent rotation of the body relative to the bore, and means for sliding said valve body within said bore to interchangeably place said orifice in open communication with said outlets.

7. In a spout-shower fixture, a casing having a bore open at one end and permanently closed at the other and provided with opposed spout and shower outlets between said ends, a removable closure for the open end of said bore, a nozzle fixedly secured to said casing at said permanently closed bore end and extending eccentrically within and along said bore, said nozzle having at least one liquid jet delivery orifice directed toward said spout outlet, a tubular valve body having a top closure movable along said bore and cooperable with said removable closure and with said nozzle to limit the movement of the body and said body also having openings at the opposite sides thereof communicable with said spout and shower outlets, and means for moving said valve body along said bore.

8. In a spout-shower fixture, a casing having a bore provided at its opposite sides with substantially alined spout and shower outlets, a fixed nozzle extending eccentrically within and along said bore, said nozzle having an orifice spaced from but directed toward said spout outlet, a hollow valve body having segregated openings communicable with said spout and shower outlet, and means for sliding said body within said bore.

5 9. In a spout-shower fixture, a casing having a bore provided with segregated spout and shower outlets, a hollow valve body slidable within said bore and having segregated spout and shower openings communicable with said outlets, a nozzle secured to said casing and extending eccentrically of said bore within said body to provide a crescent shaped chamber directly communicable with said spout outlet through said spout opening, said nozzle having one liquid discharge orifice directed across said chamber in line with said outlets and also having another orifice communicating with said chamber remote from the outlets, and means for sliding said valve body along said bore and said nozzle.

10 10. In a spout-shower fixture, a casing having a bore provided with segregated spout and shower outlets, a hollow valve slidable within said bore and having a local opening freely communicable with said spout outlet and also having a slot remote from said opening freely communicable with said shower opening, a liquid supply nozzle secured to said casing eccentrically of said bore and extending along said slot to prevent rotation of said valve body, said nozzle having an orifice for directing a liquid jet into said body in alinement with said spout outlet, and means for sliding said body along said bore and said nozzle.
